UNITED STATES PATENT OFFICE.

SAMSON D. WRIGHT, OF CLEVELAND, OHIO.

DUMP-CAR.

1,115,365.

Specification of Letters Patent. Patented Oct. 27, 1914.

Original application filed February 9, 1910, Serial No. 542,932. Divided and this application filed December 6, 1912. Serial No. 735,188.

To all whom it may concern:

Be it known that I, SAMSON D. WRIGHT, a citizen of the United States, residing at Cleveland, in the county of Cuyahoga and State of Ohio, have invented certain new and useful Improvements in Dump-Cars, of which the following is a specification.

This invention relates generally to dump cars and particularly to the door construction as applied to such cars, and forms a division of my original application Serial No. 542,932, filed February 9, 1910.

More specifically the invention contemplates in the construction of a dump car the use of a door construction whereby one edge of the door fits in an offset in the floor of the car and is provided with a wear strip engaging the shoulder formed by the offset thereby producing a tight fit to prevent the loss of the fine particles of coke termed "breeze."

The invention may be further briefly summarized as consisting in the construction and combination of parts hereinafter set forth in the following description, drawings and claim.

Referring to the drawings, Figure 1 is an end elevation of a dump car provided with my invention showing parts in section; Fig. 2 is a side elevation of the mechanism about the door showing the door closed; Fig. 3 is a similar view with a portion of the door broken away to show the shoulder formed by the offset; and Fig. 4 is a detail view of a portion of the door mechanism showing a modified form of shoulder and wear strip.

In carrying out the invention any preferred form and construction of car may be provided with my invention provided it possesses the necessary characteristics, but I have shown one form and construction in the drawings which is very effective in operation and in such embodiment 1 represents a suitable truck provided with the usual wheels 2. This truck supports a main framework 3 upon which the body 4 is mounted. This body is provided with an inclined floor 5 sloping from one side of the car to the other and at the low side extending to a suitable opening which is adapted to be closed by suitable doors 6. The floor of the car is provided with an offset at 7 forming

an outwardly extending platform 8 lower than the surface of the main floor 5. The offset at 7 forms a shoulder at this point and this shoulder is adapted to limit the movement of the doors when they are shifted into closed position. The lower inside edge of each door is provided with a wear strip 9 preferably of angle iron and adapted to fit snugly into the angle of the offset, thereby forming a tight joint between the door and the floor of the car. By the arrangement of the joint with the offset the loss of breeze or small particles of coke is prevented and by the use of the wear strip this joint may be kept tight from time to time as the particles of coke cut into the inner corner of the door:

The doors are held shut by suitable latches pivoted upon a shaft 11 extending along the underside of the floor, and this shaft is adapted to be rocked in any suitable manner as by an arm 12 extending beyond the outer edge of the floor. Suitable weighted arms 13 are provided upon this shaft to throw the latches normally into engagement with the door.

In the modification shown in Fig. 4 the doors 14 are swung on arms 15 pivoted upon pins 16 mounted in the car, and these doors are swung upon these pins so as to close the opening in a chute member 17 forming part of the car body. The floor of the car is provided with a similar offset and the door is provided with a flat wear strip 18 which fits into the angular corner formed by the offset.

Having described my invention, I claim:

In a dump car, in combination, suitable trucks, a frame, a car body having a discharge opening on one side, an inclined floor for such body having a ledge along the edge of the floor at the discharge opening and lower than the same, thereby forming a shoulder, a door for closing said discharge opening and arranged to swing above said ledge and engage said shoulder, and a wear strip along the inner lower corner and coöperating with the shoulder and the ledge.

In testimony whereof I affix my signature in presence of two witnesses.

SAMSON D. WRIGHT.
